(57) **CLAIM**

The ornamental design for a handguard for firearm as shown and described.

DESCRIPTION

FIG. 1 is a perspective view of a handguard for firearm showing the new design;

FIG. 2 is a perspective view thereof;

FIG. 3 is a perspective view thereof;

FIG. 4 is a perspective view thereof;

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a rear view thereof.

The broken lines are included for the purpose of illustrating features that form no part of the claimed design. The break lines that separate parts of the handguard for firearm and the portion outside of these break lines represent indeterminate length and form no part of the claimed design. The appearance of any portion of the handguard for firearm between the break lines form no part of the claimed design.

1 Claim, 9 Drawing Sheets
